METHOD OF AND SYSTEM FOR ELIMINATION OF FADING

Application filed November 17, 1927, Serial No. 233,802. Renewed November 21, 1931.

An object of this invention is to minimize or overcome the fading of radio telegraphic and telephonic signals, or other electro radiant transmissions.

5 It is also an object of this invention to direct the transmission of radio signals.

It is a further object of this invention to improve the quality of the signals received by the receiving station.

10 Many uses for the present invention exist which together with other objects will become apparent upon consideration of the following specification.

As is well known, during a period of transmission at any given point, sufficiently remote from the receiver, the received signals may be strong for a period of time and then become gradually weak until they almost or completely disappear.

15 At a later time the signals will increase and finally build up to as large a value as before the diminishing occurred. The period of these phenomena or fading and strengthening of the signals may be of the order of from one to two minutes corresponding approximately to the frequency of fading of .01 cycles per second.

20 The hypothesis upon which this invention is based is that the fading pattern depends upon the condition of the Heaviside or ionized layer and the consequent reflection and interference between the directly transmitted waves and the reflected waves. The shifting of the Heaviside layer therefore causes changes in the fading pattern and accounts for the phenomena known as fading.

25 As is well known certain loops and nodes will appear in the electro-static field produced by any antenna, their location or grouping being dependent upon the relationship between the length of the antenna and the frequency being transmitted. In the present invention this phenomena is utilized and transmission is accomplished over a plurality of 30 antennæ each of which have different loop and node patterns. Each loop and node pattern will result in a distinct fading pattern for a given period of time and thus if the fading pattern is changed due to shifting 35 from one antenna to the other at a super-

sonic frequency, the fading pattern may be completely changed at a supersonic rate and thus fading at any given locality greatly diminished or entirely eliminated.

Having now briefly described my invention 35 attention is called to the drawing wherein Fig. 1 represents a pair of transmitting antennæ of various lengths, each of which has a series of reflecting antennæ cooperating therewith.

Fig. 2—A shows an antenna adapted to be excited by such frequencies that the loops will appear at the angles of approximately 35° and 65° respectively. Fig. 2—B shows an antenna adapted to be excited by the same 40 frequency and of such length that a loop will appear at an angle of 50° approximately.

Fig. 3 shows the transmitter circuit by which the elimination of fading is accomplished according to my invention.

Referring now more particularly to the drawing in Fig. 1, 10 and 11 represent two vertical antenna systems which are adapted to be excited by the output 12 and 13 respectively of the same transmitting system 45 and operated at the same frequency. The reflecting antennæ 10¹, 10², 10³, are arranged and spaced from 10 in such a manner that the transmission 10 will be directed as desired in the usual and well known manner, a similar series of antennæ 11¹, 11², 11³, is arranged to direct the transmission from 11 in the same direction. The reflectors are the same geometrically as their corresponding 50 driving antennæ and in each series are arranged one quarter wave length from it in the direction opposite the desired direction of transmission and one half wave length from it at right angles to the line of transmission. It is to be understood that any desirable number of reflecting antennæ may be used.

Referring now to Fig. 1—A, there is shown an antenna 10 the same as the antenna 10 of Fig. 1 which is adapted to radiate a wave form which has a loop at a vertical angle of 55 35° and 65° approximately. Referring to Fig. 2—B, the antenna 11 is adapted to be excited by the same frequency and is of such a characteristic that a loop appears at an angle of approximately 50° or intermediate 60

of the 35° and 65° of Fig. 1—A. The radiations from these antennæ will be directed against the Heaviside layer in such different directions that there will be different places wherein the direct and reflected waves interfere or in other words different fading patterns will result from the various antennæ.

Referring now more particularly to Fig. 3 which shows a transmitter adapted to transmit the signals in accordance with my invention there is shown at 16 a thermionic device of the ordinary type including plate 17, grid 18 and filament 19, the latter of which is adapted to be supplied by the low potential source 20 and adjusted in the usual manner for producing oscillations. The plate circuit of the said device includes the inductance 21 and the high potential source 22, the former of which is inductively coupled to the inductance 23 included in the grid circuit of said device. The frequency of the oscillation circuit thus produced is adapted to be regulated by means of the condenser 24 shunted across the inductance 23 and the output of said oscillator is adapted to be supplied to the grids 26 and 27 of the tubes 28 and 29 respectively.

The tubes 28 and 29 constitute radio frequency amplifiers for supplying the antennæ 10 and 11 respectively and include the filaments 32 and 33 which latter are supplied by the low potential sources 34 and 35 respectively. Included also in said amplifier tubes are the plates 38 and 39. Included in the plate circuits are the output coils 14 and 15 and the condensers 36 and 37. For supplying a high potential to the plates of the thermionic amplifiers 28 and 29 there are provided the circuits including 40 and 41 constituting the two halves of the split secondary of the transformer 25, the audio frequency choke 42 and the high potential source 43.

For supplying an audio frequency a transmitter 44 or other suitable source is provided, which is adapted to supply an audio frequency oscillating current through the battery 45 to the primary 46 of the transformer 47. The secondary 48 of the transformer 47 is adapted to supply voice frequency current to the grid 50 of the thermionic modulator device 51 through the grid bias source 49. The device 51 is provided with a plate 54 and a filament 52, the latter of which is adapted to be supplied by a low potential source 53. The plate circuit of the modulator 51 is completed through the audio frequency choke 42 and the high potential source 43.

For shifting the transmission from antenna 10 to antenna 11 and vice versa there is provided the supersonic frequency alternator 55, or any other suitable device which is adapted to feed the coil 56 of the trans-

former 25 with a high potential supersonic alternating frequency.

Having now described my invention I will briefly describe its operation. The oscillator 16 and its associated circuits is adapted to produce a high frequency series of oscillations, which oscillations are amplified by means of the amplifiers 28 and 29 and supplied through the coils 14 and 15 and the inductively related coils 12 and 13 to the antennæ 10 and 11 respectively. The plate circuit of each of the said amplifier tubes 28 and 29 is completed through the split secondary of the transformer 25 and through the choke 42 to the source 43 and thus by means of said choke the current in said circuit is adapted to be varied by the output of the amplifier 51 as effected by the audio frequency in the usual and well known manner. The oscillator 55 supplies an alternating frequency current to the primary of the transformer 25 the secondary of which is adapted to augment the natural high voltage potential from one of the amplifier tubes at the same time that it decreases it on the other amplifier tube. The frequency of the alternator 55 is sufficiently high that the output of the two antennæ is varied at a supersonic frequency and thereby transmission pattern is varied at a supersonic frequency from that shown in Fig. 2—A to that shown in 2—B and vice versa. Consequently the fading pattern is varied at a supersonic frequency and reception at any given point is uninterrupted with respect to audio frequency and fading is partially or wholly eliminated. The transmission is directed in a horizontal plane by the reflecting antennæ and is directed in a different vertical angle by the two systems. This type of signal may be received either by a simple receiving system with a radio tuned non-oscillating first detector, and amplifier, or as an alternative by a double detection receiver. In the latter case the frequency of shift from one antenna system to the other or the frequency 55 would constitute the intermediate frequency.

Thus it can be seen that I have disclosed a method which will greatly reduce the amount of fading by a rapid shifting of the fading patterns for any given locality.

It is to be understood that I have described but one embodiment of my invention in the above specification and do not desire to be limited thereby but only by the scope of the appended claims.

I claim:

1. The method of eliminating fading in the reception of radiant energy which comprises non-directionally transmitting energy in such a manner as to have two distinct fading patterns and cyclically varying the amount of energy transmitted in accordance with the respective fading patterns.

2. The method of eliminating fading in the

reception of radiant energy which comprises transmitting energy non-directionally in such a manner as to have two distinct fading patterns and inversely varying the amount of energy transmitted in accordance with the respective fading patterns.

3. The method of eliminating fading in the reception of radiant energy which comprises transmitting energy in such a manner as to have two distinct fading patterns having different loop and node characteristics and transmitting the energy in accordance with said fading patterns, in such a manner that at alternating times the energy is transmitted almost exclusively in accordance with one of said patterns and the other of said patterns, respectively, and during the intervening interval, transmitting inversely varying amounts of energy in accordance with the respective fading patterns.

4. The method of eliminating fading in the reception of radiant energy which comprises causing electrical oscillations to cyclically vary the vertical angle of maximum radiation of the transmitted energy, while maintaining non-directional horizontal transmission patterns.

5. The method of eliminating fading in the reception of radiant energy which comprises non-directionally transmitting energy in such a manner as to have a plurality of wave forms each of which is adapted to have its vertical angle of maximum radiation at a different angle, and electrically and cyclically varying the amount of transmission over each of the various wave forms and thereby the vertical angle of maximum transmission.

6. The method of eliminating fading in the reception of radiant energy which comprises transmitting energy in such a manner as to have different wave forms each of which has a different vertical angle of maximum transmission and transmitting a normally constant amount of energy by the two wave forms in such a manner that at alternate times the energy is transmitted substantially exclusively over one wave form or the other wave form, and during the intervening period transmitting inversely varying amounts of energy over the respective wave forms.

7. The method of eliminating fading in the reception of radiant energy which comprises transmitting energy in such a manner as to have different wave forms, each of said wave forms having different vertical angles of maximum transmission, transmitting a normally constant amount of energy by the said wave forms and varying the amount of energy transmitted by each of said wave forms at a supersonic frequency so that the energy is transmitted substantially exclusively over one wave form or another wave form, at alternate times and during the intervening periods transmitting inversely varying amounts of energy over the respective

wave forms, and varying the total amount of transmission to send a signal.

8. The method of radio signalling which comprises radiating high frequency energy in a plurality of wave forms, each of which forms has different vertical directional properties, but uniform horizontal directional properties, varying the transmission of the energy among the wave forms at a rate lower than the frequency of radiation and higher than an audio frequency, and modifying the total radiated energy for the purpose of signalling.

9. The method of radio signalling which comprises causing the energy radiated in a plurality of wave forms having different vertical directive characteristics but uniform horizontal directional properties to increase and decrease at a relatively high rate without substantial change in the total energy radiated, varying the nature of total energy at a slow rate for the purpose of signalling, and horizontally directing the total transmission.

10. A transmitter for the reduction of fading in reception, comprising means for generating continuous electrical oscillations, two vertical antennæ, and means for impressing said oscillations upon the various antennæ in cyclically varying amounts.

11. A transmitter for radiant energy comprising means for generating continuous electrical oscillations, two vertical antennæ, and means for impressing said oscillations substantially alternatively on said antennæ at a predetermined frequency.

12. A transmitter for radiant energy comprising means for generating continuous electrical oscillations, a plurality of non-directional substantially vertical antennæ, and means for causing said oscillation to be impressed at different times substantially exclusively on the various antennæ and to cause energy to be impressed upon said antennæ at the intermediate period in inversely varying amounts.

13. A transmitter for radiant energy comprising means for generating a series of continuous electrical oscillations, two non-directional vertical antennæ, means for impressing said series of electrical oscillations upon the antennæ, means for causing a second series of electrical oscillations at a frequency different from that of first mentioned series of oscillations to cause the first mentioned series of oscillations to be impressed upon the two antennæ alternatively in cyclically varying portions, and a system of reflecting antennæ for horizontally directing the transmission from each of first said mentioned antennæ.

14. A transmitter for radiant energy comprising a vacuum tube oscillator for generating continuous electrical oscillations, two non-directional vertical antennæ, means for impressing said electrical oscillations upon

- the antennæ, means for cyclically alternately varying the proportion of said oscillations impressed upon the various antennæ, said last mentioned means including an oscillator for producing oscillations of different frequency from that of the first mentioned oscillations, a three electrode control tube inserted in the supply circuit of each of said antennæ and having their grids connected to the output circuit of the vacuum tube oscillator and a plurality of reflecting antennæ associated with each of said first mentioned antennæ for horizontally directing the transmissions from each of said antennæ.
15. A transmitter for radiant energy comprising means for generating continuous electrical oscillations, two non-directional vertical antennæ, means for impressing said oscillations upon said antennæ and means for horizontally directing the direction of transmission from said antennæ.
16. A transmitter for radiant energy comprising means for generating continuous electrical oscillations, two vertical antennæ having different loop and node transmission patterns, means for impressing said oscillations upon the said antennæ, means for cyclically varying the proportion of energy transmitted to each of said antennæ, and a plurality of reflecting antennæ associated with and directing the transmission of each of said first mentioned antennæ.
17. The steps in a method of signalling which comprise, generating a carrier wave, generating waves corresponding to signals desired to be transmitted, separately modulating different portions of the carrier wave by said signals and transmitting the various resultant modulated portions at different and varying intensities, said variations in intensity occurring at different spacial angles.
18. In a transmission system a source of high frequency energy adapted to be used as a carrier, a pair of amplifiers having input and output circuits, means for impressing energy from said source upon the input circuits of each of said amplifiers in like sense said output circuits including a common portion comprising a modulator circuit having associated therewith a source of signal currents, said modulator circuit being adapted to modulate the carrier energy by the signal currents, an antenna circuit associated with the output of one of said amplifiers for transmitting the signal modulated carrier energy, said antenna circuit having a predetermined loop and node pattern, a second antenna circuit associated with the other of said amplifiers also for transmitting signal modulated carrier energy said second named antenna circuit having a predetermined loop and node pattern but unlike the pattern of the first mentioned antenna, a source of supersonic frequency energy and means including a coupling between said last named source and both said output circuits for varying cyclically the amounts of energy radiated from each antenna.
19. In a signalling system a source of high frequency energy, a pair of radio frequency amplifiers having input and output circuits, means for coupling said source of high frequency energy across each of said input circuits, said output circuits including a common portion having a source of direct current for supplying each of said amplifiers with space current, a variable resistance shunted across said source of direct current and means including a source of signalling energy for controlling said variable resistance whereby the high frequency energy impressed across said input circuits through said coupling is modulated by the signalling energy, an antenna circuit having a predominant loop and node pattern coupled to the output of one of said amplifiers, a second antenna circuit independent of the first antenna circuit having a predominant loop and node pattern unlike said first antenna coupled to the output of the amplifier, a transformer having a primary coil and a divided secondary coil, one division thereof being connected in one output circuit and the other division thereof in the other output circuit, a source of varying voltage and means for connecting the primary coil across said last named source, the varying voltage impressed from said last named source through said transformer acting to periodically affect the efficiency of the amplifiers at the frequency of the voltage variation.

JOHN HAYS HAMMOND, JR.
